Office Action issued for Chilean Application No. 202102910, dated Mar. 3, 2023.

Primary Examiner — Cynthia Ramirez*Assistant Examiner* — Tamara L Hahn(74) *Attorney, Agent, or Firm* — Bauer and Joseph(57) **CLAIM**

The ornamental design for a rotary bit lifter, as shown and described.

DESCRIPTION

FIG. 1 is a perspective view showing my new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken lines shown in the drawings depict portions of the rotary bit lifter that form no part of the claimed design.
